United States Patent Office.

JOSHUA T. KENDALL, OF CONCORD, NEW HAMPSHIRE.

Letters Patent No. 76,467, dated April 7, 1868.

IMPROVEMENT IN MACHINES FOR BORING WAGON-HUBS.

The Schedule referred to in these Letters Patent and making part of the same.

Be it known that I, JOSHUA T. KENDALL, of Concord, in the county of Merrimack, and State of New Hampshire, have invented an Improvement in Machines for Boring the Hubs of Carriage-Wheels for the reception of boxes; and I do hereby declare that the following is a full and exact description thereof, and of the construction and operation of the same, reference being had to the annexed drawings making a part of this specification, in which drawings—

Figure 1 is a side elevation of my improvement.

Figure 2 is an end elevation thereof.

Figure 3 is a plan, showing the adjustment and operation of the parts composing the revolving table, shown in fig. 1 at *k*.

Figure 4 is a drawing of the gauge.

To enable others skilled in the art to make and use my invention, I will proceed to describe its construction and mode of operation.

I construct a framework of timber, of suitable form, as shown in the drawings. To this framework I adjust the driving-shaft *A*, upon which is fixed the broad pulley *b*. This shaft is made to revolve by pulleys and beltting, attached to the upper end thereof, not shown in the drawings, because forming no part of my invention.

I also adjust the screw-shaft *c*, as shown, which is made to revolve at the proper degree of speed, as hereafter explained, by pulleys and belts applied at the upper end thereof, but not shown, because no part of my invention. The said pulleys are so-adjusted that the motion of said screw-shaft may be arrested or reversed at pleasure.

I construct the metallic frame *c'* substantially as shown, and through one end of the same passes the screw-shaft, *e*, a female screw being cut therein, to correspond with the screw upon said shaft, and it will be seen that, by the revolution of the shaft, the frame *c'* will be carried up or down as the shaft is made to revolve.

In the other end of my frame I place the spindle *x*, which is made to revolve with a very high degree of speed from a belt from the broad pulley *b* on the driving-shaft *A*. Said spindle is constructed at its lower extremity, so that cutting-tools of various forms may be adjusted therein, as may be adapted to the work required to be done. One of said tools is shown in the drawing at *d*, fig. 1.

To this metallic frame I attach a gauge, which is shown upon the drawings at *e* and *e'*, which gauge is composed of two parts, the horizontal arm *e* and the vertical arm *e'*, which arms swing upon a hinge at one extremity of each, and engage with each other at the other extremity. In the vertical arm I place the set-screw *f*, and on the horizontal arm I place the set-screw *f'*, the use of which I will hereinafter more fully explain.

I also attach to said frame a spring, *g*, which is placed upon the side opposite to my gauges *e* and *e'*, and I also attach to my framework of wood a guide or pattern, shown at *h*, fig. 2, which may be adjusted at any required angle by the thumb-screws *i* and *i'*, figs. 1 and 2.

I construct a turn-table, or revolving platform, *k*, as follows: First, I construct a circular platform, having in the centre of the same a circular aperture, *k'*, of the proper size, which must, of course, be larger than the largest hub to be subjected to the operation of the machine. This platform rests upon a rim, *l*, which is firmly attached to the supports *m m'*, fig. 1, but the platform may be caused to perform a partial revolution upon said rim at pleasure by means of a wrench applied to the pinion of the ratchet-wheel, which projects through the surface of my table for that purpose at *n'*, figs. 1 and 2, and said platform and rim may be firmly clamped together by means of the clamp-screws *s''*, figs. 2 and 3, also operated by a wrench, and projecting through the surface of my table for that purpose.

Upon the under surface of my platform I place the levers or arms *p p p*, working upon pivots at *p' p' p'*, engaging with the rim in slots at *q q q*, and provided with the blocks or chucks at *r r r*, the inner end; each of which blocks or chucks is to be made of wood in a working machine, and are also attached to the arms or levers, so as to play upon pivots at *p' p' p'*.

I also provide the clamps *s' s'' s'''*, for holding the table and rim loosely in their relative positions, but so that the platform may revolve upon the rim, and I cause a screw from one of my clamps, say *s''*, to project through the surface of my table, to be operated by a wrench at *s''*, as above described, so that the platform and rim may be clamped firmly together in any desired position.

I adjust the ratchet-wheel so that the teeth engage with teeth cut to correspond with the said ratchet-teeth in the rim *l*, and by means of this ratchet-wheel moved by the pinion thereof projecting through the upper surface of my platform, to which I apply a wrench, as above mentioned, I cause the platform to revolve on the rim, as above suggested, and for the purpose hereafter explained.

The whole turn-table revolves upon a pivot at *t*, figs. 1 and 2. The lower edge of my rim is provided with a flange, as shown, and the upper flange is made by allowing the edge of the platform to project for that purpose. I pass a cross-belt, *u*, round the table between said flanges, and round the pulley *v* on the main driving-spindle, and thus cause the platform to revolve slowly in a direction contrary to the direction of the revolutions of my spindle.

To illustrate the operation of my machine, I will suppose I have to bore a hub for the reception of a four-inch box. It will be seen that the hub must be bored with a tapering hole, smaller at the outer than at the inner end, to correspond with the box, and that the aperture must be larger in the centre, so that the ends of the spokes may not rest directly on the cast-iron box, and so be liable to break the same when the wheel is subjected to a sudden shock by striking an obstacle.

I first adjust the guide to give the proper taper, and the guide is also shaped to give the requisite enlargement in the centre of the hub under the spokes. I screw in the set-screw, and, by turning out or in, as may be desirable, the set-screw *f*. I adjust my spindle in the proper position for a four-inch hole. The size of the hole is regulated by turning out or in the set-screw *f'*. As this acts against the edge of the guide *p*, it will be seen that by turning said screw out, the spindle will be forced in the opposite direction, and away from the centre of the turn-table.

I then place the wheel to be operated upon, upon my turn-table *k*, with the small end of the hub projecting downward between the blocks or chucks, and by applying my wrench to the pinion of the ratchet-wheel, I cause said blocks or chucks to close firmly round the hub, and hold it in place directly over the centre of the turn-table, and by the use of the clamp *s''* the wheel is held steadily in place.

I then start my machine, and the spindle, revolving rapidly, as above explained, descends through the hub by the action of the screw-shaft.

As the turn-table, with the wheel thereon, at the same time revolves in a direction contrary to the revolution of the spindle, it will be seen that the cutting-tool will, as it starts into the hub at one side of the centre, cut a hole therein larger than the tool itself, and as the cutting-tool is allowed to descend, it approaches nearer the centre and the hole becomes smaller, until, at the lower end of the hub, it is of the size required, the shape and taper of the bore longitudinally being governed by the shape of the guide, and the size of the hole being regulated by the distance of the spindle from the centre by the set-screw, and the taper by the inclination at which the guide is adjusted by the set-screw *f*.

In case a very large box is to be fitted, it is impracticable to complete the boring at one operation of the machine. I, in such case, loosen the set-screw *f*, which allows the spindle to work nearer the centre, and pass it through the hub, and then, by tightening said screw, readjust my machine for the final operation. But hubs of ordinary size are bored ready for the boxes at one operation of my machine.

I claim as my invention, and desire to secure by Letters Patent—

1. The guide *h'*, in combination with the gauge-arms *e* and *e'*, the set-screws *f* and *f'*, the metallic framework *c'*, and the spring *g*, substantially as described.
2. The revolving table *k*, with the arms or levers *p p p*, and chucks *r*, and ratchet-wheel *n*, and clamp *s''*, combined and operated as described.

JOSHUA T. KENDALL.
